ROTARY SWIVEL

Guglielmo R. Tremolada, Los Angeles, Calif., assignor to Emco Derrick & Equipment Company, Los Angeles, Calif., a corporation of California

Application March 23, 1945, Serial No. 584,372

19 Claims. (Cl. 255—25)

1

My invention relates to rotary swivels employed for the suspension of drill pipe during the drilling of wells by the rotary method, and relates in particular to improvements in means for carrying the drilling fluid—ordinarily referred to as rotary or drilling mud—from the rotary hose through the mud passages of the swivel to the upper end of the drill pipe string.

In present practice the rotary mud is conducted into the upper end of the swivel by means of a gooseneck which is bolted at one end to the top of the swivel structure and has a curved tubular portion which has somewhat the shape of an inverted U, the outer end of this tubular member being connected to the rotary hose so that the considerable weight of the rotary hose applies an eccentric loading to the central superstructure of the swivel to which the end of the gooseneck opposite the hose connection is secured. It is an object of the present invention to avoid the several disadvantages and difficulties produced by the accepted practice referred to in the foregoing.

It is an object of the invention to provide a simple and effective means whereby the load of the rotary hose is removed from the gooseneck. An advantage of my new arrangement is that breaking of studs or screws employed in attaching the gooseneck, owing to the overhanging load of the rotary hose, is avoided. A further disadvantage overcome by the present invention is the disalignment of cooperating parts of the swivel fluid joint or connection, a part of which swivel fluid connection is connected to the bracket on the top of the swivel shell to which the end of the gooseneck is bolted, which disalignment results from distortion of the bracket referred to in the foregoing as the result of the application thereto of the overhanging weight of the rotary hose.

Another object of the invention is to provide a rotary swivel wherein removal of worn parts of the swivel fluid connection of the rotary swivel may be accomplished without the necessity of disconnecting the rotary hose from the swivel. In accordance with old practice, the swivel fluid connection employs interfitting tubular parts with packing between these parts for preventing leakage, one of the interfitting parts being connected to the upper end of the rotating body of

2

the rotary swivel, so as to rotate with this body, and the other of the interfitting parts being connected to the bracket which is mounted upon the upper part of the shell of the rotary swivel so as to be held in cooperative relation without rotation. An extensive practice followed in the renewal of worn parts of the swivel fluid connection requires disconnection of the rotary hose from the swivel or the provision of means for supporting the weight of the rotary hose in the derrick while the gooseneck is disconnected from the top of the swivel in order to gain access to parts of the swivel fluid connection for purpose of replacement or repacking.

15 It is an object of the invention to provide a rotary swivel having on the side of its shell a rigidly secured mud inlet duct, this mud inlet duct having an upper opening and a downwardly faced or lower opening to which the rotary hose is permanently connected, the middle walls or structure of this mud inlet duct transmitting the load of the rotary hose directly to the side of the shell of the rotary swivel, so that the load of the rotary hose is not transmitted to the superstructure or bracket of the swivel which carries a part of the swivel fluid connection.

20 A further object of the invention is to provide a rotary swivel having a mud inlet duct rigidly secured to its shell in lateral relation thereto and a separate mud inlet passage member for connecting the upper end of the mud inlet duct to the mud passage which lies on the axis of rotation of the rotary swivel.

25 A further object of the invention is to provide a rotary swivel having a mud inlet duct rigidly secured to the side wall of its shell and a curved mud conveying member, replaceable when it has become worn, this mud conveying member being adapted for bolting to the top of the rotary swivel so as to connect the upper end of the mud inlet duct with the mud passages of the rotary swivel leading directly to or forming a part of the rotary fluid swivel connection of the device.

30 It is a further object of the invention to provide a rotary swivel having the characteristics and advantages referred to in the foregoing, this rotary swivel having a removable mud conveying member at the top thereof, which may be disconnected without the necessity of disconnecting

the rotary hose, and a simple wash pipe or swivel fluid connection so related to the cooperating structure that it may be readily replaced and/or repacked when the mud conveying member is removed in the manner explained in the foregoing.

A further object of the invention is to provide in this swivel fluid connection an improved wash pipe having a rubber mounting element thereon which yields sufficiently to compensate for small disalignment in the cooperating relatively rotatable parts of the swivel fluid connection and thereby relieves strain on the packing.

A further object of the invention is to provide a swivel fluid connection for use in a rotary swivel, this swivel fluid connection having an improved stuffing box which may be assembled on a work bench and which does not require adjustment when it is placed on the rotary swivel for the reason that it has a stop which determines its position and has predetermined internal parts associated with the packing material or rings thereof for applying a predetermined pressure to such packing material or rings. A feature of my present invention resides in the provision of the swivel fluid connection as a unit or cartridge, including the wash pipe and the packing means, which unit may be easily placed in operative position in the rotary swivel.

Further objects and advantages of the invention will be brought out in the following part of the specification.

Referring to the drawings which are for illustrative purposes only,

Fig. 1 is a partly sectioned side view of a preferred form of my invention.

Fig. 2 is an enlarged fragmentary sectional view of the upper portion of Fig. 1.

Fig. 3 is a fragmentary schematic view showing how parts are removed from the device.

Fig. 4 is an enlarged fragmentary sectional view showing an alternative form of my invention using the swivel fluid connection assembly.

Fig. 5 is an enlarged fragmentary quarter section taken on the plane indicated by the line 5—5 of Fig. 4.

Fig. 6 is a cross section taken as indicated by the line 6—6 of Fig. 4.

Fig. 7 is a partly sectioned view showing another form of my invention.

In the form of the invention shown in Fig. 1 the rotary swivel includes a shell 10 which is hung in a derrick by means of a bail 11, and a rotatable body 12 which extends vertically through the shell 10 and has therein an axial mud passage 13 for conveying drilling mud into the upper end of a string of drill pipe 14 which is connected to the lower end of the rotatable body 12. The cover portion 15 of the shell 10 has a laterally projecting wall 16 which supports at a side of the upper portion of the shell a mud inlet duct member 17, the lower end of which is internally threaded to receive the hose connection 18 by which a rotary hose 19 is connected to the mud inlet duct 20 of the member 17.

The laterally extending wall 16 and the mud inlet duct member 17 form a rigid connection with the cover portion 15 of the shell 10, and in the preferred practice of the invention, the parts 15, 16, and 17 are cast from steel in a single casting operation. The weight of the rotary hose 19 is transmitted from the mud inlet duct member 17 through the lateral wall 16 directly to the shell.

The cover portion 15 of the shell 10 includes an upwardly extending wall 21 which is curved

around the vertical axis of the rotary swivel through an angle or arc of nearly 180°. At the upper end of this wall 21 there is a support 22 which takes the form of a horizontal plate or flange which extends laterally in rightward direction, as shown in Fig. 1, so as to engage the upper end of the tubular mud inlet duct member 17. As clearly shown in Fig. 2, the cover 15, the laterally projecting wall 16, the member 17, the wall 21, and the horizontal supporting wall 22 are cast integral, the upper end of the mud inlet passage 20 opening at its upper end through the rightward portion of the wall 22.

As best shown in Fig. 2, the support 22 has a counterbored opening 23 concentric with the axis of rotation of the body 12 to receive the upper portion of a packing element 24, which forms part of a fluid swivel assembly or unit 25 which has the function of conveying the rotary mud from stationary passage parts of the rotary swivel to the rotating passage parts or body 12 thereof. A mud conveying member 26 is removably bolted on the upper face of the support 22. This mud conveying member 26, which may be referred to as a gooseneck, has therein a passage 27 curved to inverted U shape and connecting the upper end of the mud inlet duct 20 with the upper end of the swivel fluid connection 25, the passage 27 being gradually tapered or reduced diametrically and having its smallest portion defined by a replaceable insert 28.

In addition to the packing element 24, the fluid swivel fluid connection 25 includes a wash pipe 29 which is secured on the upper end of the rotatable body 12 so that the flared passage 30 of the wash pipe 29 will communicate with the upper end of the mud passage 13 of the body 12. The packing element 24 includes a shell 31 having an annular space to receive packing means 32 which includes a plurality of chevron packing rings 33, a grease lantern 34, and a packing compressing ring 35 disposed so that it will be engaged and forced downward by the lower wall 36 of the mud conveying member 26 when this member 26 is installed in operative position as shown.

The wash pipe 29 has on the upper external portion thereof a layer of hard wear resisting material 37, such as glass, for engagement with the packing rings 33. This feature of the invention contributes to long wearing life of the wash pipe 29. In order to minimize wear on the packing rings 33, the invention embraces a yieldable supporting ring 38 which surrounds the lower portion of the wash pipe 29, to permit the wash pipe 29 to have a small lateral movement or small lateral yieldability to compensate for small disalignment which may exist in the means for supporting the wash pipe 29 and the packing element 24, thereby reducing the pounding action between the rotating wash pipe and the stationary assembly of packing rings 33 which generally results from disalignment of the rotating and non-rotating parts. The ring 38 is formed from rubber and is bonded onto the lower external surface of the wash pipe 29. The rubber element 38 has an upwardly faced shoulder 39 which is engaged by a slip ring 40 adapted to be engaged by a clamping ring 41 which threads onto the upper threaded portion 42 of the body 12. In the upper face of the body 12 there is a shallow recess 43 of slightly larger diameter than the lower end of the wash pipe 29, to provide a clearance between the wash pipe and the body 12 and permit movement of the wash pipe which is suspended or held in position by the rubber ring 38 which is clamped

against the upper face of the body 12 by the clamping arrangement consisting of the clamping ring 41 and the slipring 40.

An important advantage of the invention relates to the ease of removing the swivel assembly 25 for replacement or repair. As shown in Fig. 3, the mud conveying member 26 may be removed from the support 22 and then, after unscrewing the clamping ring 41, the entire assembly 25 may be lifted through the opening 23, taken to a bench for inspection or for replacement of the packing element 24, which exists as a cartridge or complete assembly ready to be placed upon the upper exterior portion of the wash pipe 29. Also, this packing assembly 24 may be replaced without unscrewing the clamping ring 41 by merely removing the worn packing assembly 24 upwardly through the opening 23 after removal of the mud conveying member 26, without disconnecting the rotary hose 19 from the swivel.

The wall 16 by which the mud inlet duct member 17 is connected to the shell 10 of the swivel is hollow and defines a chamber 44 which communicates with the interior of the shell 10 through an opening 45. This chamber 44 comprises an oil expansion reservoir in communication with the interior of the shell 10 and has an opening 46 in its upper part closed by a breather plug 47 equipped with a breather passage 48 for escape of gases or fumes from the interior of the shell and equalization of interior-exterior pressures. One wall 49 of the chamber 44 is formed by a portion of the mud inlet duct member 17 which is in contact with the relatively cold entering mud. Therefore this wall 49 serves as a means for cooling the fluids in the chamber 44. The chamber 44 is so positioned with relation to the oil filling plug P of the shell that in it an oil level, such as indicated at 50, may be maintained, above the level of the uppermost bearing 51 within the shell 10, thereby assuring ample lubrication of all of the swivel bearings at all times.

The swivel fluid connection 25 has been shown in Fig. 2 with its wash pipe connected to the body 12 so as to rotate. It will be understood that this swivel fluid connection may be inverted so that the wash pipe will be stationary and the packing element 24, then being connected to the upper end of the rotatable body 12, will rotate with such body externally of the stationary wash pipe. In Fig. 4 I have shown this form of the invention, and have also shown how the swivel fluid connection may be arranged so as to be removed laterally from its operative position instead of upwardly. With reference to Fig. 4, it will be noted that a swivel fluid connection 25' is provided having a packing element shell 31' which is internally threaded instead of being flanged, so that this shell 31' may be screwed onto the threaded portion 42 at the upper end of the rotatable body 12. In this practice of the invention a flanged adaptor 52 is inserted in the opening 23 of the support 22 and is held in place by a fluid conveying member 26' which omits the nozzle 28 shown in Fig. 2. This adaptor 52 has a downwardly projecting externally threaded portion 53 which the clamping ring 41 may be screwed for the purpose of holding the wash pipe 29 in depending position with the now lower end thereof projecting into the packing element 24' to engage the packing rings 33 therein. When it is desired to remove the swivel fluid connection as an assembly for the purpose of replacement

or repair, the shell 31' may be screwed upwardly out of engagement with the threaded portion 42 of the body 12, and the clamping ring 41 may be screwed downwardly out of engagement with the threaded portion 53 of the adaptor 52, whereupon the assembly 25' may be moved laterally from its position between the parts 12 and 52.

The invention relieves from the workman who replaces the packing element 24 the responsibility for adjusting the pressure on the packing material consisting of the chevron rings 33. The shell 31' or 31 of the packing element 24 is adapted to assume a predetermined position when it is in place in the rotary swivel and therefore it is expressly prevented from movement except for purpose of adjustment. As shown in Fig. 4, the shell 31' is screwed down against the stop consisting of a gasket 55 carried by the body 12. The packing compressing ring 35, which forms a part of the packing element, is made of yieldable material and of such characteristic form that when it is compressed as the result of the screwing of the shell 31' down into its operative position, it will apply a predetermined proper pressure to the packing means consisting of the rings 33. As shown in Fig. 5, the ring 35 comprises a cylindric wall portion 58 having at the lower end thereof an inwardly faced lip 59 for engagement with the upper end face of the body 12. On the upper end of the wall portion 58 there is a rounded prominence or bead 60 shaped so that it will fit into the lowermost channel of the assembly of packing rings 33. The packing compressing ring 35 is of such vertical dimension when it is relaxed, as shown in Fig. 5, that when the shell 31' is screwed down into its operative position, the upper end of the body 12 will compress the ring 35 to such extent that the proper pressure for holding the sealing rings 33 will be exerted upwardly against the assembly of sealing rings 33. The cylindric wall portion 58 of the ring 35 is of such diameter that it will lie against a portion of the inner face of the shell 31', and around the upper portion of the ring 35 there is an inwardly projecting lip 61 arranged to be forced upwardly by fluid pressure exerted in the space 62 when mud is being pumped through the mud passages of the swivel, thereby sealing the upper edge of the ring 35 while at the same time the lip 59 will maintain a tight sealing engagement with the upper end face of the body 12. In Fig. 7 those parts which have been previously described are identified by the numerals adopted in the original description thereof. Herein I have shown the improvements consisting of the rigidly mounted mud inlet duct member and the separately removable gooseneck or mud conveying member in a swivel arrangement wherein a wash pipe 65 of a simple tubular form is rigidly mounted so that its rear end will project downwardly into a packing element 24, which is screwed onto the upper end of the rotatable body 12 of the swivel.

The supporting wall 22 of Fig. 7 has an opening 23 aligned with the axis of rotation of the body 12, there being a countersink 66 at the upper end of the opening 23 to receive a tapered portion of a narrow flange 67 which is formed on the upper end of the wash pipe 65. When it is desired to recondition the swivel fluid connection formed by the wash pipe 65 and the packing element 24, the fluid conveying member 26 may be removed from the support 22 without necessity for removing the rotary hose from attachment to the swivel, and the wash pipe 65 may be lifted

from the position in which it is shown. The packing element 24 may be then unscrewed from the body 12 and removed entirely from the swivel assembly, thereby making it possible for the workman to replace the packing therein with marked ease and facility as compared to the work involved in replacing packing in situ in the rotary swivel assembly. When the wash pipe 65 becomes worn, it may be conveniently replaced by a new duplicate part.

The wall 21 is disposed between the mud inlet duct member 17 and the fluid swivel connection 25, and as clearly shown in Figs. 1 and 6, extends only partway around the swivel fluid connection so as to leave a large opening 21' for access to the swivel fluid connection.

A feature of this part of the invention is that by the arrangement of walls shown, the opening 21' through which access to the swivel fluid connection is gained, extends through an angle of about 180°, or slightly greater, thereby providing a continuous space from one side to the other of the swivel connection 25 in which tools may be operated with much greater facility than is possible in rotary swivels employing the old diametrically opposed webs for supporting the common gooseneck.

I claim as my invention:

1. In a rotary swivel, the combination of: a shell and a rotatable body, said shell having a laterally projecting hollow wall, the interior of which communicates with the interior of said shell so as to form an oil chamber, and a mud inlet duct supported by said hollow wall at one side of said shell and having the outer end thereof prepared for connection to a rotary hose, whereby the weight of said rotary hose will be transmitted directly to the side of said shell, and said body having a mud passage therein for connection to the upper end of a string of drill pipe; a swivel fluid connection at the upper end of said passage; and a detachable mud conveying member removably secured on the top portion of said shell for conveying mud from said mud inlet duct member to said swivel fluid connection said mud conveying member being removable from its operative position without disconnection of said inlet duct member from said shell.

2. In a rotary swivel, the combination of: a shell and a rotatable body, said shell having supported on one side of its vertical axis a mud inlet duct member with an opening for connection to an end of a rotary hose, a supporting member connected to said shell in a position spaced from the upper end of said body and having an opening substantially aligned with the axis of rotation of said body, and said body having a mud passage extending vertically therethrough and adapted to be connected to the upper end of a string of drill pipe; a swivel fluid connection insertable through said opening so as to be connected to the upper end of said body, said connection comprising a wash pipe part and a packing part, one of said parts being adapted to be connected to said body and the other of said parts being adapted to be connected to said supporting member, and the upper of said parts being secured in said opening when said swivel connection is in its operative position; and a removable mud conducting member conveying to said supporting member and to the upper part of said mud inlet duct member for conveying mud from said duct member to the upper end of said swivel fluid connection, said mud conveying member, when removed from said supporting member, ex-

posing said opening so that said upper of said parts of said swivel connection may be raised with relation to said opening.

3. In a swivel fluid connection unit for a rotary swivel, the combination of: a cylindric wash pipe having a ring of rubbery material on one end thereof, said ring providing a forwardly faced shoulder, said wash pipe having a cylindric layer of hard material on its other end; a clamping ring to engage said shoulder; and a packing element surrounding said layer of hard material on said wash pipe, said packing element comprising a shell forming a packing space, a packing means in said space and a compressing ring of rubbery material in the outer end of said space, said compressing ring having a cylindric wall to engage the wall of said shell, an inwardly directed sealing lip at the outer end of said compressing ring and an inwardly directed sealing lip at the inner end of said compressing ring, there being a bead on the inner end of said compressing ring to engage said packing means.

4. In a swivel fluid connection unit for a rotary swivel, the combination of: a cylindric wash pipe having a ring of rubbery material on one end thereof, said ring providing a forwardly faced shoulder, said wash pipe having a cylindric layer of vitreous material on its other end; a clamping ring to engage said shoulder; and a packing element surrounding said layer of vitreous material on said wash pipe, said packing element comprising a shell forming a packing space, a packing means in said space and a compressing ring of rubbery material in the outer end of said space, said compressing ring having a cylindric wall to engage the wall of said shell, an inwardly directed sealing lip at the outer end of said compressing ring and an inwardly directed sealing lip at the inner end of said compressing ring, there being a bead on the inner end of said compressing ring to engage said packing means.

5. In a rotary swivel, the combination of: a body and a shell in rotatable relation, said shell having supported on one side thereof a mud inlet duct member with an opening for connection to an end of a rotary hose, and said body having a mud passage therein for connection to the upper end of a string of drill pipe; a supporting member extending in spaced relation to the top of said shell and to the upper end of said body, said supporting member being connected to the upper end of said mud inlet duct member; a swivel fluid connection at the upper end of said passage, having the lower portion thereof connected to the upper end of said body and having the upper portion thereof supported by said supporting member; a wall disposed between said mud inlet member and said swivel fluid connection and connecting the top of said shell to said supporting member; and a mud conveying member carried by said supporting member for conveying mud from said mud inlet duct member to said swivel fluid connection, said mud conveying member being removable from said supporting member independently of said mud inlet member.

6. In a rotary swivel, the combination of: a body and a shell in rotatable relation, said shell having supported on one side thereof a mud inlet duct member with an opening for connection to an end of a rotary hose, and said body having a mud passage therein for connection to the upper end of a string of drill pipe; a supporting member extending in spaced relation to the top of said shell and to the upper end of said body, said supporting member being connected to the upper

end of said mud inlet duct member; a swivel fluid connection at the upper end of said passage, having the lower portion thereof connected to the upper end of said body and having the upper portion thereof supported by said supporting member; a wall disposed between said mud inlet member and said swivel fluid connection and connecting the top of said shell to said supporting member, said wall extending partway around said swivel fluid connection and leaving an opening faced away from said mud inlet duct member for access to said swivel fluid connection; and walls forming an extension of the passage of said mud inlet duct member for conveying mud from said inlet duct member to said swivel fluid connection.

7. In a rotary swivel, the combination of: a body and a shell in rotatable relation, said shell having supported on one side thereof a mud inlet duct member with an opening for connection to an end of a rotary hose, and said body having a mud passage therein for connection to the upper end of a string of drill pipe; a supporting member secured to said shell in spaced relation to the upper end of said body, said supporting member having an opening spaced from the upper end of said body, and being also connected to the upper portion of said mud inlet duct member; a swivel fluid connection movable laterally into and out of the space between the upper end of said body and said supporting member, said swivel fluid connection having the lower portion thereof connected to the upper end of said body and having the upper portion thereof supported by said supporting member; and a mud conveying member carried by said supporting member for conveying mud from said mud inlet duct member to said swivel fluid connection, said mud conveying member being removable from said supporting member independently of said mud inlet member.

8. In a rotary swivel, the combination of: a body and a shell in rotatable relation, said shell having supported on one side thereof a mud inlet duct member with an opening for connection to an end of a rotary hose, and said body having a mud passage therein for connection to the upper end of a string of drill pipe; a supporting member secured to said shell in spaced relation to the upper end of said body, said supporting member having an opening defined by a downwardly projecting annular wall spaced from the upper end of said body, and being also connected to the upper portion of said mud inlet duct member; a swivel fluid connection movable laterally into and out of the space between the upper end of said body and said supporting member, said swivel fluid connection having means for connecting the lower portion thereof to the upper end of said body and having means for connecting the upper portion thereof to said annular wall which projects downwardly from said supporting member; and a mud conveying member carried by said supporting member for conveying mud from said mud inlet duct member to said swivel fluid connection.

9. In a rotary swivel, the combination of: a shell and a rotatable body, said shell having supported on one side of its vertical axis a mud inlet duct member with an opening for connection to an end of a rotary hose, whereby the weight of said rotary hose is transmitted directly to said shell, and said body having a mud passage therein for connection to the upper end of a string of drill pipe; a swivel fluid connection at the upper

end of said passage; and a mud conveying member on the top of said shell having an inverted U-shaped passage for carrying mud from said mud inlet duct member to said swivel fluid connection, said mud conveying member being detachable from its operative position without disconnection of said inlet duct member from said shell.

10. In a rotary swivel, the combination of: a shell and a rotatable body, said shell having supported on one side of its vertical axis a mud inlet duct member with an opening for connection to an end of a rotary hose, whereby the weight of said rotary hose is transmitted directly to said shell, and said body having a mud passage therein for connection to the upper end of a string of drill pipe; a swivel fluid connection at the upper end of said mud passage; and a detachable mud conveying member removably secured on the top portion of said shell for conveying mud from said mud inlet duct member to said swivel fluid connection, said mud conveying member being detachable from its operative position without disconnection of said inlet duct member from said shell.

11. In a rotary swivel, the combination of: a shell and a rotatable body, said shell having supported on one side of its vertical axis a mud inlet duct member with an opening for connection to an end of a rotary hose, and said body having a mud passage therein for connection to the upper end of a string of drill pipe; a supporting member secured to said shell in vertically spaced relation to the upper end of said body, said supporting member being also secured to the upper portion of said mud inlet duct member; a swivel fluid connection at the upper end of said passage, having the lower portion thereof connected to the upper end of said body and having the upper portion thereof supported by said supporting member; and a mud conveying member carried by said supporting member for conveying mud from said mud inlet duct member to said swivel fluid connection, at least a portion of said mud conveying member being detachably connected so as to expose the upper part of said swivel connection while the weight of the rotary hose is carried by the shell.

12. In a rotary swivel, the combination of: a shell and a rotatable body, said shell having supported on one side of its vertical axis a mud inlet duct member with an opening for connection to an end of a rotary hose, and said body having a mud passage therein for connection to the upper end of a string of drill pipe; a supporting member secured to said shell in vertically spaced relation to the upper end of said body, said supporting member being also secured to the upper portion of said mud inlet duct member, said supporting member having an opening therein aligned with said passage of said body; a swivel fluid connection at the upper end of said passage, having the lower portion thereof connected to the upper end of said body and having the upper portion thereof supported by said supporting member, said swivel fluid connection being of such size that an operative part of it may be removed as a unit upwardly through said opening in said supporting member; and a mud conveying member carried by said supporting member for conveying mud from said mud inlet duct member to said swivel fluid connection, at least a portion of said mud conveying member being detachable so as to expose said opening to permit removal of said part of said swivel connection.

13. In a rotary swivel, the combination of: a shell and a rotatable body, said shell having supported on one side of its vertical axis a mud inlet duct member with an opening for connection to an end of a rotary hose, a supporting member connected to said shell in a position spaced vertically from the upper end of said body and having an opening substantially aligned with the axis of rotation of said body, and said body having a mud passage extending vertically therethrough and adapted to be connected to the upper end of a string of drill pipe; a swivel fluid connection adapted to be connected to the upper end of said body, said connection comprising a wash pipe part and a packing part, one of said parts being adapted to be connected to said body and the other of said parts being adapted to be connected to said supporting member, and at least the upper of said parts being insertable into operative position through said opening in said supporting member; and a removable mud conveying member connected to said supporting member and to the upper part of said mud inlet duct member for conveying mud from said duct member to the upper end of said swivel fluid connection, said mud conveying member holding said upper of said parts in its operative position when said mud conveying member is connected to the upper part of said mud inlet member.

14. In a rotary swivel, the combination of: a shell and a rotatable body, said shell having supported on one side of its vertical axis a mud inlet duct member with an opening for connection to an end of a rotary hose, a supporting member connected to said shell in a position spaced from the upper end of said body and having an opening substantially aligned with the axis of rotation of said body, and said body having a mud passage extending vertically therethrough and adapted to be connected to the upper end of a string of drill pipe; a swivel fluid connection having a wash pipe insertable downwardly through said opening of said supporting member; and a mud conveying member connected to said supporting member and to the upper part of said mud inlet duct member for conveying mud from said duct member to the upper end of said swivel fluid connection, said mud conveying member being movable independently of said mud inlet duct member so as to disclose said opening and permit upward movement of said wash pipe with relation to said opening.

15. In a rotary swivel, the combination of: a shell and a rotatable body, said shell having supported on one side thereof a mud inlet duct member with an opening for connection to an end of a rotary hose, a supporting member connected to said shell in a position spaced from the upper end of said body and having an opening substantially aligned with the axis of rotation of said body, and said body having a mud passage extending vertically therethrough and adapted to be connected to the upper end of a string of drill pipe; a swivel fluid connection having a wash pipe and having a securing ring for the upper end of the wash pipe disposed in said opening of said supporting member and packing means connected to the upper end of said body; and a mud conveying member connected to said supporting member and to the upper part of said mud inlet duct member for conveying mud from said duct member to the upper end of said swivel fluid connection, said mud conveying member being movable independently of said mud

inlet duct member so as to permit movement of said securing ring in said opening.

16. In a rotary swivel, the combination of: a shell and a rotatable body, said shell having supported on one side thereof a mud inlet duct member with an opening for connection to an end of a rotary hose, a supporting member connected to said shell in a position spaced from the upper end of said body and having an opening substantially aligned with the axis of rotation of said body, and said body having a mud passage extending vertically therethrough and adapted to be connected to the upper end of a string of drill pipe; a swivel fluid connection, comprising a wash pipe, a packing shell, and packing means in said packing shell, the upper of said parts extending downwardly from said opening of said supporting member; and a mud conveying member attached to said supporting member and connecting the upper part of said mud inlet duct member to the upper end of said swivel fluid connection for conveying mud from said duct member to the upper end of said swivel fluid connection, said mud conveying member being movable independently of said inlet duct member so as to permit upward movement of the upper of said parts of said swivel connection relatively to said opening.

17. In a rotary swivel, the combination of: a shell and a rotatable body, said shell having a laterally projecting hollow wall projecting above the level of the uppermost bearing means in said shell, the interior of which communicates with the interior of said shell so as to form an oil chamber, and a mud inlet duct supported by said hollow wall at one side of the vertical axis of said shell and having the outer end thereof prepared for connection to a rotary hose, and said body having a mud passage therein for connection to the upper end of a string of drill pipe; a swivel fluid connection at the upper end of said passage; and a mud conveying member removably connected to the upper end of said mud inlet duct and to the upper end of said swivel fluid connection for conveying mud from said mud inlet duct member to said swivel fluid connection.

18. In a rotary swivel, the combination of: a shell and a rotatable body, said body having a mud passage therein for connection to the upper end of a string of drill pipe; a removable swivel fluid connection at the upper end of said mud passage; and mud conveying means for conducting mud from a rotary hose to the upper end of said swivel fluid connection, said mud conveying means having an inlet wall portion connected to said shell whereby the weight of the rotary hose is transmitted directly to said shell, and said mud conveying means defining an inlet offset to a side of the vertical axis of said swivel fluid connection for connection to the rotary hose, and a wall portion defining an outlet from said mud conveying means to the upper end of said swivel fluid connection, said mud conveying means having a detachable wall portion movable to uncover the upper end of said swivel fluid connection without disconnection of said inlet wall portion of said mud conveying means from said shell.

19. In a rotary swivel, the combination of: a shell and a rotatable body, said body having a mud passage therein for connection to the upper end of a string of drill pipe; a removable swivel fluid connection at the upper end of said mud passage; and mud conveying means for conducting mud from a rotary hose to the upper end of said swivel fluid connection, said mud convey-

13

ing means having an inlet wall portion connected to said shell whereby the weight of the rotary hose is transmitted directly to said shell, and said mud conveying means defining an inlet offset to a side of the vertical axis of said swivel fluid connection for connection to the rotary hose, and an outlet wall portion defining an outlet for flow of mud from said mud conveying means to the upper end of said swivel fluid connection and having a downwardly faced opening through which at least a portion of said swivel fluid connection may be vertically moved, said mud conveying means having a detachable wall portion movable to uncover said opening to enable access to the upper end of said swivel fluid connection without disconnection of said inlet wall portion of said mud conveying means from said shell.

Certificate of Correction

January 18, 1949.

Patent No. 2,459,472.

GUGLIELMO R. TREMOLADA

It is hereby certified that errors appear in the printed specification of the above numbered patent requiring correction as follows:

Column 5, line 69, after the numeral "53" and before the word "which", insert *on*;
column 7, line 70, claim 2, for "conducting member conveying" read *conveying member connected*; column 14, line 7, list of references cited, for "Nov. 2, 1931" read *Nov. 3, 1931*;

and that the said Letters Patent should be read with these corrections therein that the same may conform to the record of the case in the Patent Office.

Signed and sealed this 7th day of June, A. D. 1949.
